UNITED STATES PATENT OFFICE.

PAUL H. SUHLING, OF CHICAGO, ILLINOIS.

MECHANICAL PICTURE.

1,012,747.

Specification of Letters Patent. Patented Dec. 26, 1911.

Application filed October 11, 1911. Serial No. 654,059.

To all whom it may concern:

Be it known that I, PAUL H. SUHLING, citizen of the United States, residing at Chicago, in the county of Cook and State 5 of Illinois, have invented certain new and useful Improvements in Mechanical Pictures; and I do hereby declare the following to be a full, clear, and exact description of the invention, such as will enable others 10 skilled in the art to which it appertains to make and use the same.

This invention has for its object to provide a mechanical picture and consists in the features of construction and combinations of parts hereinafter described, and 15 claimed.

In the accompanying drawings illustrating the invention: Figure —1— is a view in front elevation of a picture constructed 20 in accordance with my invention. Fig. —2— is a vertical sectional view of the same on the line 2—2 of Fig. —1—.

The invention is particularly applicable to picture post cards and the like bearing 25 representations of various animals, and consists essentially in providing the representation of the animal with a mechanical tail which projects from the picture and is very elastic so that the same will move or swing 30 easily upon imparting movement to the card or device bearing the picture.

In the instance illustrated the representation 35 of a donkey is shown, this pictorial representation being minus the tail. Se- 40 cured to the card A or other device bearing the pictorial representation B at the point in the picture at which the tail of the donkey should be attached is a coiled spiro- helical spring C which is tapered to a point 45 at its free end. The said spring A is se- cured to the card, or the like, by passing an end coil of the spring through a perforation in the card as shown at D, and by then turning the spring in the manner of a screw said 50 end coil E becomes disposed upon and bears against the under face of the card A or the like. The said end coil may then be relatively firmly secured against removal by disposing upon the under face of the card, 55 or the like, and covering the end coil E of the spring by disposing a small strip F

of gummed paper, or the like, which ad-heres to the card and the said end coil D of the spring.

By reason of the elasticity of the spring 55 C constituting a substitute for the pictorial representation of the tail, the same will easily swing or wag, as will be obvious, and may be folded down to lie flat upon the card so that the latter may be readily inserted in 60 an ordinary envelop for purposes of mailing.

The device is intended exclusively for amusement, as will be obvious.

I claim as my invention:

1. As a new article of manufacture, a 65 card bearing the pictorial representation of an animal devoid of its tail, and an elastic spring secured to said card at one of its ends at the point of attachment of the tail of the 70 animal pictured thereon and projecting from the pictorial face of the card.

2. As a new article of manufacture, a 75 card bearing the pictorial representation of an animal devoid of its tail, and an elastic helical spring secured to said card at one of its ends at the point of attachment of the tail of the animal pictured thereon.

3. As a new article of manufacture, a 80 card bearing the pictorial representation of an animal devoid of its tail, and an elastic helical spring secured to said card at one of its ends at the point of attachment of the tail of the animal pictured thereon, said spring tapered toward its free end portion. 85

4. As a new article of manufacture, a 90 card bearing the pictorial representation of an animal devoid of its tail, and having a perforation at the point in the picture at which the tail of the animal is attached to the body, a helical spring secured at one 95 end in said perforation and tapered at its free end, and means engaging said spring with said card for preventing withdrawal thereof from said perforation.

In testimony whereof I have signed my name in presence of two subscribing witnesses.

PAUL H. SUHLING.
